PIPE THREADING DIESTOCK

Henry Landsman, Poughkeepsie, N. Y.

Application October 1, 1946, Serial No. 700,520

8 Claims. (Cl. 10—127)

1

This invention relates to a die stock of the type employing a fixed or buttonhead die such as is commonly used for the threading of pipe.

One of the objects of my invention is a die stock for the aforementioned purpose which can be used for threading pipe in close places or in places where only a limited protruding end of the pipe to be threaded is accessible, or in recessed places where the available working diameter and depth is too limited for the conventional die stock to be used.

Another object of the invention is a die stock which will hold a circular pipe die within a cylindrical casing having no protuberances or projections at its outer surface, so that the casing may be entered into the small circular spacing surrounding a pipe in a fixed installation.

An allied object is a die stock provided with means for turning at one end thereof so that the die stock can be turned from the end of the cylindrical casing which protrudes from the said space surrounding the pipe.

The further object is a die stock which can be turned by the common type of operating handle, such as a ratchet handle, or by a wrench applied to one end of the cylindrical casing.

For the attainment of the foregoing and such other objects of invention as may appear or be pointed out herein, I have shown one embodiment of my invention in the accompanying drawing, wherein

Fig. 1 is a side view of the improved die stock;

Fig. 2 is an end view as seen from the forward or pipe-entering end (right end, Fig. 1);

Fig. 3 is the opposite end view as seen from the rear or driving end (left end, Fig. 1);

Fig. 4 is a side sectional elevation taken on the line 4—4 of Fig. 2; and

Fig. 5 is a cross-sectional view taken on the line 5—5 of Fig. 4.

The improved die stock comprises a cylindrical casing 10 whose outer surface is of a generally uniform diameter; the casing diameter is of the minimum dimension for receiving the die therein, and the length of the casing is likewise held to a minimum. The cylindrical surface of the casing is entirely free of any projections or protuberances, so that a pipe in a fixed installation can be threaded by the improved device even though the space surrounding its end or through which the pipe end can be reached is extremely limited. It is sufficient that the surrounding space be somewhat larger than the cylindrical casing 10. This ability of the improved die stock to operate in small round openings is due not

2

only to the absence of projections or protuberances or the like on the outer surfaces of the cylindrical casing and that the diameter thereof is held to the over-all dimension of the die, but also to the fact, as will be more fully explained subsequently, that the improved die stock may be turned from the end protruding from the opening.

Casing 10 is provided with a central bore which extends throughout its length and is formed of three connecting sections each of different diameter and length and each serving a different purpose, as will be seen. Bore section 11 opens at the forward end of the die stock (in which end the pipe is entered), i. e., the right end of casing 10, Fig. 4, and is of the largest diameter of the three sections. The next section 12 opens into end section 11 and is of somewhat smaller diameter, which results in an annular shoulder 14 between bore sections 11 and 12. Bore sections 11 and 12 are cylindrical whereas the third section 13 is square (but may have any other non-circular outline). Section 13, which opens at the opposite end of casing 10 (left end, Fig. 4) and enters into intermediate section 12, is of considerably smaller cross-section than the two cylindrical sections 11 and 12.

The lengths of the three sections 11, 12, 13 differ as will be seen in Fig. 4. The end section 11 is made of a length or depth to accommodate the thickness of pipe die 20 and of a sufficiently large diameter to snugly receive the die with one face seated on annular shoulder 14 and the other face substantially flush with the forward or right end, Fig. 4, of the casing. This diameter of end section or die pocket 11 determines the over-all diameter of casing 10; the latter diameter is held to the minimum dimension that will provide a wall 15 of sufficient thickness to permit a tapped hole to be cut therethrough. Such tapped hole in casing wall 15 is for set-screw 16 which serves to hold die 20 against rotation and axial movement. Two such set-screws 16 are shown spaced 180° apart, although a different number or holding arrangement may be used.

The intermediate section 12 serves to receive the cuttings or debris resulting from the pipe threading operation. Intermediate section or cuttings chamber 12 is open to the outer surface of cylindrical casing 10 so that the cuttings or debris may be cleared from the device. Four holes 17, 90° apart, are shown, see esp. Fig. 5, although a different number and spacing may be used.

Non-circular section 13 serves two purposes,

and it is by reason of both purposes that it is made non-circular in section. And it is also because it serves two purposes that it is considerably longer than the other sections, being in fact about one-half the length of casing 10. One of these functions is to hold a guide pin 30 which enters into the pipe being threaded; the other purpose is to accommodate a driving or turning handle, as will be seen. Guide pin 30, which is tapered 31 at its forward end to facilitate entrance into the pipe or nipple, has an enlarged non-circular butt end 32 which is conveniently shown as square although it may be given any other non-circular section. Accordingly, section 13 is made square in section and of a dimension to snugly receive butt end 32 of the guide pin. The invention contemplates that the butt end of the guide pin and section 13 be made square in order that it may accommodate the square lug present on the standard driving handle, and of the proper size to receive it.

Butt end 32 of the guide pin is entered into section 13 as shown in Fig. 4 and positioned with its shoulder 33, on the side of the butt from which pin 30 projects, substantially flush with the inner wall 18 of cuttings chamber 12. Butt end 32 is provided with countersunk cups or depressions 34 on each of its four sides which contact the respective four sides of square bore section 13. Casing 10 is drilled and tapped for a single set-screw 35, see Fig. 3, which will enter one of the four depressions 34 of the guide pin irrespective of the angular position of butt end 32 relative to the casing, and will hold the guide pin in proper position as described above and shown in Fig. 4. It will be noted that the side (shoulder) 33 of the butt end closes off cuttings chamber 12 so that the debris cannot enter section 13, and that shoulder 33 is substantially flush with inner wall 18 of the cuttings chamber so that no recess is left in which debris may accumulate. In this connection it will also be observed that the cuttings clearing holes 17, see Fig. 4, is positioned so that one edge thereof is only slightly elevated, at 19, above wall 18, so that practically no space is left within which debris will stick.

Butt end 32 occupies only a part of square bore section 13, so that there is sufficient room at the open end of the section, left end of the casing, Fig. 4, for inserting the engaging end or lug of the common type of handles, such as ratchet handles, thus enabling the device to be turned from that end. That end of casing 10 may also be provided with a projecting boss 9, shown as hexagonal in Fig. 3, but which may be square or other non-circular shape, for accommodating a wrench, spanner or the like.

Die 20 may be lubricated during the threading operation by introducing a lubricant through a hole 8, see Fig. 2, provided in casing 10 at the forward or pipe end, right end, Fig. 4 (i. e., through cylindrical wall 15, Fig. 4). Die 20 itself is provided with a slit 23, Fig. 2, extending from face to face of the die, which registers with hole 8 when the die is properly seated in die pocket 11 of casing 10. Instead of a slit, a hole of smaller size than the hole 8, may be provided in the circumference of the die.

I claim:

1. In a die stock of the class described, in combination a circular pipe die, an operating handle having a square connecting lug, a cylindrical casing having a central bore extending for its full length in three sections, the section open at one end of the casing being

of somewhat greater diameter than the diameter of the die and of a length somewhat greater than the thickness of the die to serve as a pocket for the die, the intermediate section being of less diameter than that of the die pocket to provide an annular shoulder at the rear of the die pocket and serving as a chamber for the thread cuttings entering the wide central space between the die pocket and cuttings chamber, openings from the outer surface of the cylindrical casing to the interior of the cuttings chamber for discharge of the cuttings therefrom, the third bore section being of square cross-section and size to receive the said lug of the operating handle, a guide pin for inserting into the bore of the pipe being threaded by said die, said guide pin having a butt end of square outline and size to be received in the said third bore section, the latter being of sufficient length to accommodate both the said butt end of the guide pin positioned at its end adjacent the cuttings chamber and the said handle lug entered therein at its mouth at the end of the casing.

2. In a die stock of the class described, in combination, a circular pipe die, a cylindrical casing having a central core extending axially in three sections, the section open at one end of the casing being of somewhat greater diameter than the diameter of the die and of a length somewhat greater than the thickness of the die to serve as a pocket for the die, the intermediate section being of less diameter than that of the die pocket to provide an annular shoulder at the rear of the die pocket and serving as a chamber for the thread cuttings entering the wide central space between the die pocket and cuttings chamber, openings from the outer surface of the cylindrical casing to the interior of the cuttings chamber for discharge of the cuttings therefrom, the third bore section being of non-circular cross-section, a guide pin for inserting into the bore of the pipe being threaded by said die, said guide pin having a butt end of the non-circular outline of the said third bore section to be received therein, the outer surface of the cylindrical casing being free of projections or protuberances whereby the casing may be entered into a small circular space surrounding an installed pipe with one end of the casing protruding therefrom, and means at the said protruding end of the casing for turning the die stock.

3. The die stock according to claim 2 wherein the external diameter of the cylindrical casing is only sufficiently larger than the said internal diameter of its said die pocket to provide an annular wall of sufficient thickness to be tapped for a set-screw, whereby the said space into which the casing may be entered is reduced to a minimum.

4. The die stock according to claim 2 wherein the said butt end of the guide pin is positioned at the end of the said third bore section with the face thereof from which the guide pin projects flush with the inner wall of the cuttings chamber and wherein the said openings into the interior of the cuttings chamber is close to the said inner wall thereof, whereby the cuttings chamber is free of recesses wherein the cuttings could accumulate.

5. The die stock according to claim 2 wherein the sides of the butt end of the guide pin contacting the respective sides of the third bore section are each provided with a cup depression and the cylindrical casing is drilled and tapped for a single set-screw, whereby the set-screw will enter

the cup depression of any one of the sides of the butt end to hold the guide pin in proper position.

6. The die stock according to claim 2 wherein the end of the cylindrical casing at its third bore section is provided with a non-circular boss for turning the die stock by a wrench applied at that end.

7. The die stock according to claim 2 wherein the said cylindrical casing is provided with a hole at its outer surface entering into its said die pocket and the said die is slotted at its circumference to afford communications with the die threads, the die being positioned in the pocket with its slit aligned with the said casing hole wherethrough a lubricant may be introduced to reach the die threads.

8. The die stock according to claim 2 wherein the said central bore of the casing extends to and

5
6
is open at the other end of the casing and the said third section thereof is of a non-circular outline and size to receive the lug of an operating handle.
